(57) **CLAIM**

I claim the ornamental design for a rectangular shaped container assembly with a stylized base, as shown and described.

DESCRIPTION

FIG. 1 is a top isometric view of the base of the container assembly without the lid showing my new design;

FIG. 2 is bottom isometric view thereof;

FIG. 3 is a front view thereof, the rear view being a mirror image thereof;

FIG. 4 is a right side view thereof, the left side view being a mirror image thereof;

FIG. 5 is a cross sectional view of FIG. 3;

FIG. 6 is a top view of FIG. 1;

FIG. 7 is a bottom view thereof;

FIG. 8 is a top isometric view of the container assembly in assembled condition;

FIG. 9 is a bottom isometric view thereof;

FIG. 10 is a front view thereof, the rear view being a mirror image thereof;

FIG. 11 right side view thereof, the left side view being a mirror image thereof;

FIG. 12 is a top view thereof; and,

FIG. 13 is a bottom view thereof.

The broken lines are included for the purpose of illustrating environmental structure and form no part of the claimed design.
